Richard B. Hall, Cincinnati, Ohio, assignor to Dominion Electric Corporation, a corporation of Ohio

Filed July 31, 1963, Ser. No. 76,060

Term of patent 14 years

(Cl. D4—3)

FIG. 1

FIG. 3

FIG. 2

FIG. 4

FIG.5

FIGURE 1 is a front elevational view of a cabinet for electric toothbrushes embodying my design and showing the transparent cover thereof in closed position;

FIGURE 2 is an end view of the same;

FIGURE 3 is a rear elevational view of the same;

FIGURE 4 is a top plan view of the same; and

FIGURE 5 is a perspective view of the cabinet for electric tooth brushes with the transparent cover shown swung upwardly to open position.

The dominant features of my design reside in the portions shown in full lines, and the toothbrushes and power unit shown in broken lines in FIGURES 1 and 4 are included for illustrative purposes only.

I claim:

The ornamental design for a cabinet for electric toothbrushes, substantially as shown and described.
